UNITED STATES PATENT OFFICE.

ORREN ALLEN, OF DENVER, COLORADO, AND DANIEL J. O'ROURKE, OF CHICAGO,
ILLINOIS.

CAR-LOADING SYSTEM.

Application filed December 3, 1924. Serial No. 753,759.

To all whom it may concern:

Be it known that we, ORREN ALLEN and DANIEL J. O'ROURKE, citizens of the United States of America, residing, respectively, at 5 the city and county of Denver and State of Colorado, and Chicago, county of Cook, and State of Illinois, have invented a new and useful Car-Loading System, of which the following is a specification.

10 Our invention relates to a car loading system.

And the objects of our invention are:

First. To provide a system of transferring empty cars ahead of the loaded cars 15 on one railway track in tunnels that are too narrow to allow a switch to be put in without blasting out a long chamber in the side of the tunnel for the switch, and without removing the loaded cars from the track, 20 and without the employment of car switching men.

Second. To provide a system of transferring an empty rock muck car ahead of a loaded car on one track, which consists of 25 running a train of empty cars into a tunnel until the car at the head of the train of empty cars is under the muck loading machine, and then while it is being loaded, uncoupling the rear empty car and moving it 30 a short distance down the track, and lifting it off of the track and moving it far enough away from the track for the motor and the other cars in the train of cars to pass it, then moving the motor up to and 35 coupling it to the cars left in the train, and backing them down past the car off the track, and then placing the car that is off of the track back onto the track ahead of the loaded car in the train, and then pushing 40 the train of cars up to the loading machine until the empty car is in position to be loaded by it; and repeating the operation until all of the cars are filled with muck; and then pulling the train of loaded cars 45 out of the tunnel and dumping the muck out of them; and then returning the train of empty cars into the tunnel to the muck loading machine.

Third. To provide a quickly and easily 50 operated, and thoroughly practical co-operating system of empty muck-car moving, loading and manipulating mechanism for transmitting empty cars ahead of loaded

cars on one track without the use of a switch track, so that they can be loaded in successive order until all of the empty cars in the train of empty cars are filled with rock muck.

We attain these objects by the mechanism illustrated in the accompanying drawings, 60 in which:

Figure 1, is a diagrammatic perspective view of a portion of a tunnel bore and illustrating the manner of removing the muck from the breast end of the tunnel by means 65 of the improved car-handling system.

Figure 2, is a transverse sectional view through the tunnel bore, showing the pneumatically operating mechanism for transferring the muck-handling cars from the track 70 to one side thereof and then back to the track.

Figure 3, is a side view of one of the cars showing the mechanism by which either the loaded or unloaded cars are lifted, the pneumatically operated lifting cylinder being 75 omitted.

Figure 4, is a front view of one of the adjustable props for supporting the cross bar upon which is mounted the trolley which supports the pneumatically operated lifting cylinder.

Figure 5, is a horizontal sectional view on the line 5-5 of Figure 4.

Figure 6, is an enlarged vertical longitudinal sectional view through one end portion of the trolley-supporting cross bar.

Figure 7, is a transverse sectional view on the line 7-7 of Figure 6.

Figure 8, is an enlarged vertical sectional view through one of the trolley wheels and the support therefor which forms a part of the upper head of the lifting cylinder.

Figure 9, is an end elevation of the casting that connects the lower end of the piston rod to the I-beam that extends across the central portion of the length of each empty car, when moving an empty car from, and returning it to the track.

Figure 10, is a sectional view on the line 100 10-10 of Figure 3, and

Figure 11, is a plan view of a cylinder head, showing the trolley supporting brackets thereon and the trolley wheels.

Similar letters of reference refer to similar parts throughout the several views.

Referring to the drawings:

The numeral 1 designates a tunnel that is too narrow to lay either a double track or a switch in, and consequently only one track 5 2, is laid in the center of it.

In the present application of our invention, it is applied to a tunnel of about eight feet square, and our invention is now in operative use in the eight foot square preliminary, or scout tunnel, of the Moffat 10 tunnel which is being driven through the Rocky Mountains in Colorado in advance of the main full size tunnel, which will be twenty-four feet high by sixteen feet wide.

The numeral 3 designates one of the railway tracks supporting cross ties which are laid on the floor of the tunnel to support the track 2, and in Figure 2 we illustrate in two different positions one of the rock muck 15 holding cars, that conveys the rock that is blasted out of the breast of the tunnel, which is called rock muck, out of the tunnel to the dump; but in Figure 1, four of these rock muck conveying cars are illustrated, 20 and they are designated by the letters A, B, C and D, in order to describe the transferring movements of the three cars, B, C and D, as will be clearly described hereinafter, but the car shown in Figure 2 can be any 25 one of the three cars B, C or D shown in Figure 1, and consequently we have designated it BCD, in Figure 2. (The car A is not transferred.)

The letter M designates an electric motor 30 which pushes the rock muck conveying cars into the tunnel and pulls them out of it.

The numeral 5 designates the floor of the tunnel; 6 and 7 the side walls, and 8 the roof of the tunnel. 8^A designates the breast of 35 the tunnel; 8^B, rock muck that has been blasted out of the breast of the tunnel; 8^C the rock muck loading machine; 8^D the shovel of the loading machine, and 8^E the endless belt conveyor on which the shovel 40 deposits its contents and which discharges the rock muck into the head car of a train of empty cars and 8^F, the muck loader operator.

In Figure 2, we illustrate an empty muck 45 conveying car BCD, on the track 2, and above it a trolley supporting bar 9 is secured against the opposite sides 6 and 7 of the tunnel. Our invention contemplates, however, any form of a metal cross tunnel 50 trolley-supporting bar. We preferably, however, use a round cross bar, preferably a 55 tubular bar, and use a double extra strong piece of steam pipe.

Our invention contemplates any way of 60 securing the opposite ends of the trolley supporting bar against the opposite side walls 6 and 7 of the tunnel. We preferably, however, provide the opposite ends of the 65 tubular bar with a sleeve 11, which is secured by pins 10 to the tube 9 against move-

ment, and the sleeve is provided with an interior thread, in which a large-threaded short shaft 12 is threaded to turn easily. This short shaft extends a short distance through the sleeve into the tube 9, and its 70 outer end is provided with a large nut 13, which forms an integral part of it; a short bearing 14 extends beyond the nut portion of the threaded shaft, on which a two-pointed fork 15 is loosely enough mounted 75 to adjust itself to uneven surfaces on the opposite side walls of the tunnel; then, by turning the short-threaded shaft to screw it out of the tube, 9, at either one or at both ends moves the forks against the side walls 80 of the tunnel and the points of the fork press tightly against and slightly into the rock. By means of these extension forks at the opposite ends of the trolley-supporting bar, the bar is secured across the tunnel 85 against accidental displacement; and in addition to the forks, we can use, when desired, a pair of adjustable spreading props, the upper ends of the standards 16 being connected to the sides of the cross bar 9 by rings 17 90 that are formed on a clamping sleeve that is slidably mounted on the bar and is arranged to clamp the sleeve to the bar, and rings 20 that extend through the rings 17 and are secured to the upper ends of the 95 standards 16.

Upon the cross bar 9 we mount a trolley 23, which consists of a pair of sheaves 24 and a supporting frame 25. Each sheave wheel is secured to a shaft 25^A, the opposite 100 ends of which are rotatably mounted in the supporting frame. This supporting frame is illustrated as being made as an integral part of a cylinder head 26, and it forms the upper cylinder head of a cylinder 27, but 105 it may be made in two or more pieces and secured together if desired.

This trolley is arranged to run back and forth on top of the cross-bar 9 of the tunnel, and the cylinder 27 is secured to it, as well 110 as the lower cylinder head 29 of the cylinder 27, by bolts 30 that extend down through the top cylinder head, and the cylinder and its lower cylinder head and these bolts 30 115 clamp the upper cylinder head 26 and the cylinder 27 and the lower cylinder head 29 together.

A piston 31 and a piston rod 32 are reciprocally mounted in the cylinder 27, and the lower end of the piston rod is pivotally secured to a casting 33 by a pin 34, and the lower end of the casting is extended along 120 and made to surround an I-beam 35, and its opposite end portions are secured to the I-beam by bolts. The casting 33 is illustrated as being made in two half parts, but it may be made in a one piece casting and be cored out to allow the I-beam to be extended through it, if desired.

The I-beam is made long enough to extend 125

across the length of a car to its opposite ends 33^a and 34^a, and castings 36 are secured to each end, and the outer ends of the casting are provided with a bolt 34^b that extends through them at right angles to the length of the I-beam 35, and on the opposite ends of the bolts, we mount and pivotally secure to the opposite sides of the casting, the upper ends of a pair of long hooks 37, the lower ends 37^a, of which swing under the edges 40, of the angle bars 38, that are secured to the bottom 39 of the body of the car, and hook to them, the hooks being made long enough to allow their hooked ends 37^a to swing under the lower edges 40 of the angle bars 38, when the I-beam rests on the opposite end of the top edges of the car, and to hook up under the lower edges 40 of the angle bars 38 when the I-beam is raised slightly above the top of the car by air pressure admitted to the cylinder, as will be presently described.

In order to admit compressed air to the bottom of the cylinder and to admit it and exhaust it to operate the piston to raise and lower the cars 3, and to hold them in the air until they are swung to one side of the track out of the path of the passing motor and the other cars in the train, we preferably use the following arrangement of air conveying hose and air inlet and exhaust valves and pipe fittings:

We form an aperture through the lower cylinder head and thread to it one end of a nipple 41, to the opposite end of which an elbow 42 is connected and a nipple 43 is connected to the elbow 42, and a T 44 is connected to the opposite end of the nipple 43. A nipple 45 is connected to the opposite end of the T 44, and an elbow 46 is connected to the opposite end of the nipple 45. A nipple 47 is connected to the elbow 46, and a valve 48 is connected to the nipple 47. A nipple 49 is connected to the valve 48, and one end of a hose 50 is connected by a coupling 49^a to the nipple 49, the opposite end of which extends to a supply of compressed air that flows from an air compressor, and is piped through the tunnel to the rock drilling machines.

The T 44 is also provided with a nipple 51, and a valve 52 is connected to the nipple 51, and a nipple 53 is connected to the valve 52, and an elbow 54 is connected to the nipple 53.

The valve 48 is the air inlet valve, and the valve 52 is the exhaust valve, and the air exhausts from the cylinder into the atmosphere from the elbow 54.

The upper cylinder head is provided with a small vent hole 55 to let the air that works past the piston head escape to the atmosphere instead of compressing there above the piston. We illustrate a valve 55^a, connected to this vent hole in order that the size of the aperture the air escapes through

may be adjusted to the size desired to avoid compression.

An oil or grease cup 56 is also connected to the upper cylinder head to furnish lubrication to the interior of the cylinder and to the piston head, which is provided with piston rings 57.

We preferably use a cylinder with a bore of about eight inches and a length of about thirteen inches and use a piston head of about three inches in thickness, which gives us a stroke of ten inches, and consequently the piston lifts each car ten inches above the track.

The operation of our system of transferring empty rock muck cars in a train of empty cars ahead of the loaded cars as fast as they are loaded, one at a time on a single track, without the use of a switch track, is as follows:

The piston head 31, and the piston rod 32, are moved up in the cylinder 27 by compressed air, and we use in the practical operation of our empty car lifting apparatus, compressed air of about one hundred pounds pressure, as our muck cars weigh about twenty-three hundred pounds each, and this pressure of air lifts the cars quickly but not violently, and it will hold the cars in the air as long as desired.

Assuming, then, that a train of empty rock muck conveying cars is pushed into the tunnel by the motorman E and the motor M, until its head end car marked A, is under the endless muck conveying belt 8^E, of the loading machine 8^C, and the loading machine, its bucket 8^E and conveyor 8^E, are started up to shovel up and convey and discharge the rock muck into the empty car A, then while the car A is being loaded, the rear empty car D is uncoupled from the car C, and is moved by the motorman E, down the track under the air lifting apparatus AA, which is positioned about a hundred feet from the car loading machine called the muck loader.

We only show four empty cars and an electric motor in the train in the tunnel, and they are marked A, B, C, D, and the electric motor M, although as many more cars may be made up into a train as desired; and as soon as the car D is uncoupled from the train of empty cars by the brakeman F, then the motorman E of the motor M, backs the car D down under the air lifting apparatus AA; then the brakeman F, uncouples the empty car D from the motor M, and the motor is backed down the track far enough from the car D to allow the brakeman F to step to the front end O¹, of the car and he is instantly assisted by the motorman E, who steps off of the motor and walks to the back end O², of the car D. Then both of them take hold of the opposite ends of the I-beam 35, at or about the top of the hooks and roll the trolley and the cylinder, and thus swing-

ing the I-beam and the hooks over the top of the car to the center of the car D, and push the hooks 37^A, under the lower edge 40 of the angled bar 38; then the motorman E, 5 opens the air inlet valve 48, and the air pressure flowing into the cylinder raises the piston head and the piston and lifts the car and its wheels off of the track as shown in Figure 2. Then both brakeman F, and 10 motorman E, pull and swing the car towards and close to the side wall 6, of the tunnel, and and its trolley, 23, runs on the cross bar 9, close to the side wall end of the cross bar. Then the motorman E, closes the air 15 inlet valve 48, and opens the exhaust valve 52, and allows the air to escape from the cylinder to the atmosphere from the elbow 54, to allow the empty car to move down quickly but not violently onto and rest on the rock 20 floor of the tunnel as shown, but if preferred the car may be left hanging in the air, and time is saved if we let it hang, leaving the hooks hooked under the lower edge of both ends of the car. It only requires about 25 fifteen seconds to hook onto and raise and move a car off the track.

After the empty car D, has been transferred from the track to the side of the tunnel, it is far enough away from the track to 30 allow the motor and the balance of the cars in the train of cars to move past it; and then the motorman E, runs the motor up to and the brakeman couples the motor M, to the car C, and as by this time, the car A, has 35 been filled with rock muck, the motorman E, backs all of the three cars, that is, the empties C, and B, and the now loaded car A, which three cars the motorman now backs down past the air lifting apparatus, far 40 enough to allow the brakeman to jump off of the car and get into position on the opposite front end O¹, of the car D. Then the car D is rollingly swung back over the track by the motorman and the brakeman by its trolley rolling on the cross bar 9, of the tunnel, until the car D, stands over the track; then the motorman E, closes the air inlet valve, and opens the exhaust valve 52, enough to 45 allow the car D, to move down slowly onto the rails of the track; and each one guides his end of the car so its wheels move onto the rails of the track; and they thus set this empty car D, on the track again ahead of the now muck filled car A. Then the brakeman and the motorman unhook the hooks 50 from the lower edge of their respective ends of the car and they are swung over to the side wall 6, of the tunnel, by pulling on them, which causes their trolley to roll on the cross bar 9, and move the cylinder and the I-beam 55 along with it.

The motorman E of the motor then moves the train up to the replaced car D, and the brakeman couples the train to this replaced car D, and jumps on the motor, and then the

motorman E, operates the motor to push the train up the track until the empty car D, is under the conveyor of the loader.

Then the instant the empty car D, is stopped under the conveyor of the loader, 70 the conveyor is started up by its operator, who commences to fill it. The brakeman F, then jumps off the motor and uncouples the now rear car C, and jumps on the car again, and the motorman E, backs it down the track 75 until it is under the air lifting apparatus; then the brakeman F, gets off of the car, and uncouples it and walks around to the front end O², of the car; meanwhile the motor backs far enough away from the car C, on 80 the track, so that the motorman E, can get between it and the motor; then the motorman gets off the motor and both the motorman and brakeman grasp the I-beam and the hooks and pull them and the trolley and 85 the cylinder over to the center of the car C, and hook the hooks under the lower edges 40, of the angle bar 38, at its lower opposite ends; then the motorman E, after seeing that the exhaust valve is closed, opens the 90 air inlet valve, and the air raises the car C off of the track, and they swing it over to the side wall 6 of the tunnel, and either let it down or let it hang there on the hooks, and then both jump on the motor, which then 95 runs up and is coupled to the empty car B, and then backs down the track with it and with the now loaded car D, and the now loaded car A, and he backs these three cars D, A, and B, below the car C, that is off the 100 track. Then the brakeman and motorman jump off the cars D, A, and B, and the motor and go to the opposite ends of the car C, that is off of the track hanging on the trolley and grasp the opposite ends of the I-beam 105 and then the car C is swung by the brakeman and motorman over the track, and is lowered onto the tracks ahead of the loaded car D, and then the brakeman and motorman unhook it and pull the hooks and trolley away from over the track, and then the motor pushes the three cars D, A, and B, up to the replaced car C, and then the brakeman couples the car C to the loaded car D, 110 and then the brakeman F, preferably jumps onto the empty car C, and the motorman E operates the motor to move the empty car C and the two now loaded cars D and A and the empty car B, up to the conveyor with 115 the empty car C, now ahead of the car D, under the conveyor, and while the car C, is being loaded, the brakeman F, uncouples the remaining empty car B, and the motorman moves it down with the motor under the air lifting apparatus AA, and it is removed from the track the same as the other two empties were; and then the motor goes up and gets now three loaded cars C, D, and A, and pulls them back down below the removed car B, and it is replaced on the track 120 125 130

ahead of the now three loaded cars C, D, and A, and is run up under the conveyor, and loaded. Then all four of the cars, B, C, D and A, of which the train is composed, are now loaded and the motor M draws them out of the tunnel to the dump, where they are unloaded, and then they are returned to the breast of the tunnel.

The time required to set a car back on the track is generally a few seconds longer than that required to remove one from the track, as the brakeman has to be careful in guiding the cars' wheels down onto the track, but only from about thirty to forty seconds are required to remove and replace an empty car on the track ahead of a full one. In fact, an empty car can be run up and filled and backed down and another empty car set ahead of the loaded one, and run up in position to be filled in about two and one-half to three minutes, thus completing the cycle of transmitting an empty car ahead of a filled car and putting it in position to be filled on a single track, without the use of a switch track for switching the loaded cars to one side of the empty cars.

Consequently a train of about ten to twelve empty cars can be very quickly and easily loaded with rock muck at the breast of a tunnel on a single track by the use of our air lifting apparatus, and the cooperating system of train movements herein described.

Our invention provides a rapidly working system of loading dirt, rock muck, coal, ores, and other material conveying cars, not only in narrow tunnels that form the preliminary drilled small tunnels of large railroad tunnels as in the present case, but also for tunnels for conveying water through mountains, and for coal mining tunnels driven in and through veins of coal in coal mining operations, and also in the narrow tunnels generally used in mining gold, silver, copper, lead and zinc and other mineral

mining operations. Our car lifting apparatus can also be used for lifting freight cars off of one track and placing them on another track in freight yards, especially freight cars loaded with perishable fruit that cannot be gotten out of a train in a yard congested with freight trains. And a great saving is made by using our single track system in tunnels, as the expense of the cross ties and the rails and the labor of blasting out the long chambers or recesses in the sides of narrow tunnels for the switches and also the work of laying the switches, and having several men switch loaded cars by hand; and while we have illustrated and described the preferred construction of our invention, we do not wish to be limited to it, as changes may be made in it without departing from the spirit of our invention.

Having described our invention, what we claim as new and desire to secure by Letters Patent, is:

In tunnel building, a method of handling loads, which consists in running an empty train of cars to the breast of the tunnel, loading the first car, lifting an empty car from the track, moving the loaded car rearwardly past the car off the track, lifting the detached car back upon the track, moving it to the breast of the tunnel and loading it, lifting another empty car from the track, moving the last loaded car rearwardly past the car off the track, lifting the detached car back upon the track and continuing this alternate loading and shifting of cars until all cars are loaded.

In testimony whereof we affix our signature in presence of two witnesses.

ORREN ALLEN.
DANIEL J. O'ROURKE.
